UNITED STATES PATENT OFFICE.

MATHIAS BURGSTALLER, OF CLEVELAND, OHIO.

GAS BURNER.

1,426,815.

Specification of Letters Patent. Patented Aug. 22, 1922.

Application filed December 29, 1921. Serial No. 525,677.

To all whom it may concern:

Be it known that I, MATHIAS BURGSTALLER, a citizen of the United States, residing at Cleveland, in the county of Cuyahoga and State of Ohio, have invented certain new and useful Improvements in Gas Burners, of which the following is a specification.

This invention relates to gas burners, and has for its object to provide an improved burner suitable for use in gas furnaces and other heaters; or it may be attached to gas pipes in household rooms. The structure is believed to provide a burner of increased efficiency as compared to other burners for the purposes referred to.

In the accompanying drawings, Fig. 1 is a vertical section of the burner. Fig. 2 is a top plan view. Fig. 3 is a section on the line 3—3 of Fig. 1.

In the figures of the drawings, 1 indicates a vertical gas pipe having an air opening 3 through which air is admitted into the pipe to mix with the gas therein. The upper end of the pipe is provided with a cap 4 having a row of fine jet holes 5 around the same. The gas is initially ignited at these holes.

Surrounding the head of the pipe, and spaced therefrom, is a drum 7 supported by a bracket 6 on the pipe 1, this drum being closed at the top by a plate 8. The side wall of the drum has a series of jet holes 10 around the same, and on the outside of the drum, above these holes, are upper and lower circular fins or flanges 9 and 9^a, the upper flange 9^a being somewhat wider than the lower flange.

Surrounding the burner thus constructed is a larger circular shell 12, supported by brackets 11, and this shell has a top plate 13 provided with openings 14 therein controlled by a rotary damper 15 mounted on the plate 13 and having openings which may be registered or not with the openings in the top plate. The damper plate may be turned by a handle 16.

In the operation of the device, the gas is first lighted at the holes 5, and this fills the drum 7 with mixed air and flame, the shell

being open at the bottom, and after the drum becomes sufficiently heated the gases formed will also ignite and burn at the jet holes 10, producing another flame between the drum 7 and the shell 12, and this flame is deflected by the baffles 9 and 9^a against the shell 12, and in consequence the air both inside and outside the shell 12 is heated to a high degree. The initial combustion at the jets 5, being confined within the drum 7, forms a gas or product in combination with the air admitted at the bottom of the drum 7, which will burn at the openings 10. In other words it is assumed that the combustion in the drum 7 is incomplete and is completed by union of the products with the additional air entering the lower end of the shell 12 when the products of the initial combustion escape through the openings 10. Repeated operation of the device has demonstrated the existence of flame both within the drum 7 and in the space between the drum and the shell 12, and this has been found to give a superior heating capacity in proportion to the amount of gas used.

I claim:

1. A gas burner comprising a pipe head having jet openings, a drum surrounding said head, said drum being open at the bottom and closed at the top, the side wall of the drum having baffles on the outside thereof and jet openings below said baffles, and a shell surrounding the drum and spaced therefrom.

2. A gas burner comprising a pipe head having jet openings, a drum surrounding the head and spaced therefrom, the side wall of the drum having jet openings and spaced baffles above said openings, and a shell surrounding the head, said shell being open at the bottom and having openings at the top, and a damper controlling the top openings.

In testimony whereof, I affix my signature in presence of two witnesses.

MATHIAS BURGSTALLER.
